UNITED STATES PATENT OFFICE.

JOHN SCHOFIELD, OF HOLYOKE, MASSACHUSETTS.

SASH-HOLDER.

SPECIFICATION forming part of Letters Patent No. 429,364, dated June 3, 1890.

Application filed September 7, 1889. Serial No. 323,251. (No model.)

To all whom it may concern:

Be it known that I, JOHN SCHOFIELD, of Holyoke, in the county of Hampden and State of Massachusetts, have invented a new and useful Improvement in Sash-Supports, of which the following is a full, clear, and exact description.

The object of my invention is to produce a simple, cheap, and practical device which can be readily applied to new or old sash and which will support the sash reliably at different points of elevation of the lower sash or lowered adjustment of the upper sash.

With these objects in view my invention consists in the construction and combination of parts, as hereinafter described, and indicated in the claims.

Reference is to be had to the accompanying drawings, forming a part of this specification, in which similar letters of reference indicate corresponding parts in all the figures.

Figure 1 is a face elevation of a window frame and sash, the molding that forms a finish and covers the stiles of the frame being removed to expose locking-notches in the stiles, the improved sash-supports being also shown in position on the sash. Fig. 2 is a transverse section of the frame, taken on the line α α . (See Fig. 1.) Fig. 3 is an enlarged vertical section of a portion of a window-frame and the improved sash-support in position on a portion of the frame of a sash that is shown broken away to expose the sash-support; and Fig. 4 is a view in elevation of the sash-support enlarged and detached from the frame, the face, which when in position is adjacent to the window-frame, being shown.

The sash-support consists, essentially, of a bracket-frame C, having a recess or pocket C' formed therein for the reception of a plate-spring c, which latter is coiled or wrapped upon itself at each end, so as to produce volute scrolls e, that have their inner terminals affixed to the pintles f, which project from or through the parallel walls i of the bracket-frame C and are fastened thereto. The central portion of the plate-spring c is bent outwardly at c', so as to assume an elliptical or circular form, considered edgewise, and a reinforce block d, which conforms to the inner surface of the central curved portion of the spring c, is secured thereon by rivets or other

means. It is necessary that when the plate-spring c is secured in the frame C the portion supported by the block d be projected considerably outside of the pocket of the frame C, and thus adapt it to engage the notches a, which are formed at spaced intervals on each of the stiles A of the window-frame. The sash-support just described is inserted in pairs oppositely in suitable cavities excavated in the edges of the upper and lower sash-frames B B', the center swells of the springs c projecting beyond the face of the bracket-frame, so as to spring into mating notches a, as before mentioned. The series of notches a are cut in the window-stiles A in the inner faces of the same at such points as are preferred for the elevation or lowered adjustment of the lower and upper sashes, it being evident that said notches must be equal in width to that of the springs c, so as to admit freely the re-enforced portions c', and that these notches be formed in the parallel grooves usually provided for the upper and lower sash.

In use the operation of the sash-supports is automatic, as the strength of their springs c is so proportioned to the weight of the sash that these will be reliably sustained, and when a change of position of either the upper or lower sash is desired it is only necessary to push the lower sash up or pull the top sash down until the right pair of notches is engaged by the springs c, when the sash will be locked instantly. If properly constructed, but a moderate degree of force need be exerted to adjust the sash as stated.

The resilience of the volute scrolls e, formed upon the ends of the plate-springs c, affords a yielding action thereto and permits them to assume the depressed position shown in dotted lines in Fig. 3, and when pressure is relaxed to resume their normal shape, as shown in full lines in the same figure. Danger of breakage is avoided by provision of the scroll ends just named, and undue resistance to compression that would result if the ends were not rendered capable of yielding is entirely obviated by the construction of parts as described.

Having fully described my invention, I claim as new and desire to secure by Letters Patent—

1. A sash-support having a bracket-frame

and a curved plate-spring which is coiled at each end into volute scrolls that are attached to the bracket-frame, substantially as set forth.

2. A sash-support having a bracket-frame which is recessed and has parallel walls on two sides and a plate-spring that is curved outwardly from the bracket-frame near its middle and has a re-enforce block secured thereon and is further provided with volute coils

formed near its ends, which coils are secured to by their terminals to transverse pintles which are fixed in the walls of the bracket-frame, substantially as set forth.

JOHN SCHOFIELD.
